UNITED STATES PATENT OFFICE.

CHAUNCEY G. BEVIN, OF EAST HAMPTON, CONNECTICUT, ASSIGNOR TO
BEVIN BROTHERS MANUFACTURING COMPANY, OF SAME PLACE.

STRAP FOR SLEIGH-BELLS.

SPECIFICATION forming part of Letters Patent No. 228,508, dated June 8, 1880.

Application filed April 22, 1880. (Model.)

To all whom it may concern:

Be it known that I, CHAUNCEY G. BEVIN, a citizen of the United States, residing at East Hampton, in the county of Middlesex and State of Connecticut, have invented new and useful Improvements in Straps for Sleigh-Bells, of which the following is a specification.

This invention relates to certain improvements in straps for sleigh-bells of that class in which a thin metallic strap is employed in combination with an ordinary strap of leather or other equivalent material, to add to the strength and durability of the strap and provide a rigid and firm support for the bells.

My invention has for its object to produce a highly-ornamental strap, which will readily adapt itself in continuous curves to any position in which it may be applied requiring it to be bent, which will preserve its shape under ordinary usage, resume it quickly after undue or accidental temporary flexure, and obviate the liability of breakage of the metallic portion of the same, as more fully hereinafter specified.

To this end my invention consists in the combination, with an ordinary leather or other equivalent strap, of a metallic strap provided with a series of corrugations and alternate plain sections, the plain sections forming the seats for the sleigh-bells, as more fully hereinafter set forth.

In the drawings, Figure 1 represents a perspective view of a portion of my improved strap, showing the bells attached; Fig. 2, a longitudinal section of the strap and bells.

The letter A indicates a strap of leather or other equivalent pliable or flexible material, such as is usually employed for mounting sleigh-bells; and B a pad, such as is usually employed in connection with the same, of flannel, felt, or other equivalent material.

The letter C indicates a strap constructed of a thin strip of flexible metal of a length and width corresponding to the length and width of the strip A. The said strap C is corrugated transversely at certain portions of its length, as indicated at D, leaving intermediate plain portions, E, which form the seats for the bells F.

The bells F may be of the ordinary or any approved description, and their shanks are passed through suitable apertures G in the

plain portions or seats of the metallic strap and similar apertures H in the leather strap and pad, and are riveted so as to secure the straps A and C and the pad together, forming a single strap.

As constructed, it will be observed that the bells have as secure and rigid a seat upon the flat portions of the metallic part of the compound strap as if said metallic part were made flat throughout its entire length, while the corrugated portions between such seats render the metallic part of the strap not only more flexible and resilient, but obviate the usual tendency to breakage—a common difficulty to be met with in sleigh-bell straps composed partly of metal and partly of leather.

In addition to these advantages, also, the corrugations impart a highly-ornamental appearance to the strap, thereby producing a more attractive and marketable article.

I am aware that there has heretofore been patented a band or strap for sleigh-bells consisting of a continuous strip of textile or other material and a series of flexible metallic sections connected together by means of leather sections and suitable links and secured to the continuous band or strap; and I lay no claim to the invention of such a strap or band. It has not the elasticity and property of preserving its curves which characterize my present invention, in which it will be observed that while the metallic strap is continuous its corrugations permit it to elongate or contract to accommodate itself to whatever curvature may be given to the leather or textile strap.

What I claim is—

A strap for sleigh-bells, consisting of a leather strap and a flexible metallic strap, the latter being provided alternately with a series of transverse corrugations and plain sections, the plain sections serving as seats for the bells, the shanks of which pass through both straps and are riveted at their ends, whereby the straps are secured together, substantially as specified.

In testimony whereof I have hereunto set my hand in the presence of two subscribing witnesses.

CHAUNCEY G. BEVIN.
